[57] CLAIM

The ornamental design for a eyeglass flotation device, as shown and described.

DESCRIPTION

FIG. 1 is a perspective view of an eyeglass flotation device showing our new design, the broken line showing of the eyeglass frame is for illustrative purposes only and forms no part of the claimed design;
FIG. 2 is a first side view thereof with the second side view being a mirror image of the first side view;
FIG. 3 is a top plan view thereof, the bottom plan view being a mirror image of the top plan view;
FIG. 4 is a rear elevation view thereof; and,
FIG. 5 is a front elevational view thereof.
